UNITED STATES PATENT OFFICE.

CHARLES T. WAGNER, OF COLLEGE POINT, NEW YORK.

DESIGN FOR QUILTING.

SPECIFICATION forming part of Design No. 18,416, dated June 26, 1888.

Application filed February 2, 1888. Serial No. 262,831. Term of patent 7 years.

To all whom it may concern:

Be it known that I, CHARLES T. WAGNER, of College Point, Queens county, State of New York, have originated and produced a new 5 Design for Quilting, of which the following is a specification.

My design relates to quiltings which are manufactured for linings for skirts, for garments, and for bed-coverings.

10 This design consists of a number of lines severally composed of an oblique portion or ogee curve, then a semicircle, then a reversed oblique portion or ogee curve, then a reversed semicircle, and then a repetition of the oblique portions described, the several lines being so disposed that the oblique portions of each line will intersect the oblique portions of two other lines, and that the semicircles of each line will intersect the semicircles of 15 other lines.

In the accompanying drawing I have represented a piece of quilting ornamented with my design.

Each of the lines of stitching is composed 20 of an oblique portion or ogee curve, a' , a semicircle, a^2 , a reverse oblique portion or ogee curve, a^3 , a reversed semicircle, a^4 , and then successive repetitions of the oblique portions

or curves described. These lines are so disposed that each of the oblique portions or ogee curves of each line will cross oblique portions or ogee curves of two other lines, and so that each of the semicircles of each line will intersect a semicircle of another line. This combination of lines described produces the appearance of interlacing between the different lines and produces a great variety of figures, accordingly as the different portions of the intersected lines may be viewed.

What I claim as new, and desire to secure 25 by Letters Patent, is—

The design for quilting, consisting of a number of lines severally composed of an oblique portion, then a semicircle, then a reversed oblique portion, then a reversed semicircle, and 30 then a repetition of the oblique portions described, the several lines being so disposed that the oblique portions of each line will intersect the oblique portions of two other lines, and that the semicircles of each line will intersect 35 the semicircles of other lines, substantially as shown and described.

CHAS. T. WAGNER.
